UNITED STATES PATENT OFFICE

2,101,672

ROCK DRILL MOUNTING

John C. Curtis, Garfield Heights, Ohio, assignor
to The Cleveland Rock Drill Company, Cleve-
land, Ohio, a corporation of Ohio

Application March 28, 1935, Serial No. 13,524
Renewed February 23, 1937

4 Claims. (Cl. 121—9)

This invention relates broadly to rock drills, but more particularly to a drilling apparatus including a rock drill of the drifter type having a feeding mechanism associated therewith for imparting feeding motion thereto.

One object of this invention is to provide a rock drill feeding mechanism with means within which the flexible element transmitting feeding motion from the feeding mechanism to the drill 10 is slidably guided.

Another object of this invention is to produce an improved drilling apparatus of simple construction which is strong, durable and efficient.

Other objects and advantages more or less 15 ancillary to the foregoing reside in the specific construction and aggroupment of the elements peculiar to this structure, as will become apparent from a more complete examination of this specification.

20 In the drawing:

Fig. 1 is a side elevational view illustrating the drill assembly.

Fig. 2 is an enlarged longitudinal sectional view 25 of the central portion of the drill guiding frame shown in Fig. 1.

Fig. 3 is a top plan view of one end portion of the drill guiding frame.

Fig. 4 is an enlarged cross sectional view taken 30 in a plane indicated by line 4—4 in Fig. 1.

Referring to the drawing which illustrates a preferred embodiment of the invention, 10 represents a wheel supported frame having a substantially U-shaped member 11 pivotally connected thereto by suitable connections 12. Pivotally secured to the cross bar 13 of the member 11 by a clamp 14 including a bolt 15, there is a saddle 16 which is formed with a tapered socket 17 adapted to rotatably receive the conical portion 18 of a center head 19. The conical portion 18 is internally machined to operatively accommodate the head 20 of a bolt 21, which extends through the saddle to receive a nut 22 by which the center head 20 and the saddle 16 may be clamped against relative rotation.

Above the conical portion 18, the center head 19 is formed with two coaxially disposed counterbores 23 and 24 having a partition 25 therebetween. Within each counterbore is mounted one end of a tube 26 which extends outwardly therefrom to receive a cap 27 mounted on the outer end thereof. The tubes 26 and caps 27 are rigidly secured to the center head 19 by through bolts 28.

Extending upwardly from the caps 27 and the head 19, there are apertured lugs 29 having rig-

idly secured thereto by bolts 30, two parallel guides 31 disposed in spaced relation with each other and formed with the usual guideways 32 within which is slidably mounted a rock drill 33. The guides 31 and tubes 26 form together a drill guiding frame movably connected to the U-shaped member 11.

The interior of the tubes 26 is conveniently machined to accommodate the fluid actuated feeding mechanism described and shown in my 10 United States Letters Patent No. 2,029,223, dated January 28, 1936. This mechanism includes fluid actuated pistons connected to each other by a piston rod 34 slideable through the partition 25. Operatively associated with these pistons, there 15 is a flexible element or chain 35 connected to the rock drill 33 for transmitting slideable movement thereto. This chain extends externally of the tubes 26 for longitudinal movement between the guides 31.

20 Welded on each tube 26 between the guides 31, there is an elongated member 36 disposed longitudinally of the tubes, and formed with a U-shaped groove or guideway 37 within which the chain 35 is slidably guided against lateral movement. The two guides 37 are mounted in coaxial alignment with each other to form a chain guide extending substantially the full length of the drill guiding frame. The bottom wall of the guide or of the groove 37 is adequately machined 25 to provide a smooth surface on which the chain is free to slide.

Although the form of embodiment of the present invention as herein disclosed constitutes a preferred form, it is to be understood that other 30 forms might be adapted without departing from the spirit of the invention as herein claimed.

I claim:

1. A rock drill feeding and guiding mechanism comprising an elongated hollow frame, 40 a duality of elongated members secured thereon in spaced relation with each other, a guideway within each of said members within which the drill is free to slide, a fluid actuated mechanism within said frame, a flexible member 45 connecting said feeding mechanism to said drill for transmitting the movement of the former to the latter, and a stationary element extending longitudinally between said elongated members, said element having a guideway within which 50 said flexible member is free to slide.

2. A rock drill support including an elongated hollow member having a feeding mechanism therein connected to the drill by a flexible element, guideways on said member within which 55

the drill is free to slide, and elongated means longitudinally between said guideways within which said flexible element is slidably guided.

3. In a rock drill support, the combination of an elongated frame having a drill slidable thereon, of a feeding mechanism for said drill including a flexible element connected to the drill for transmitting feeding motion thereto, and longitudinally disposed guiding means on said frame

within which said flexible element is slidably guided.

4. In a rock drill, the combination of a support having a drill slidable thereon, of a feeding mechanism for the drill including a flexible element longitudinally of the support, and means on said support for guiding said element against lateral movement. 5

JOHN C. CURTIS.
